UNITED STATES PATENT OFFICE

2,390,873

FREIGHT CAR

Frank Ditchfield, Cleveland, Ohio, assignor to The Youngstown Steel Door Company, Cleveland, Ohio, a corporation of Ohio

Application June 23, 1943, Serial No. 491,865

15 Claims. (Cl. 105—376)

This invention relates to freight cars and more particularly to freight cars of the house type.

It is an object of this invention to provide house cars which shall be capable of use in the customary manner for the shipment of carload lots of commodities and which shall be readily convertible into compartments for the shipment of several less-than-carload lots of the same or of different commodities.

A further object is to provide house cars capable of being converted into separate compartments by means of bulkheads or partitions without the requirement of extraneous parts to form the bulkheads or partitions.

A further object is to provide house cars capable of being converted into separate compartments, each of which shall be independently accessible.

A further object is to provide house cars so arranged and constructed that portions of the car lining may be disposed to form bulkheads or partitions for dividing the cars into separate compartments.

A further object is to provide house cars capable of being converted into separate compartments by means of bulkheads or partitions without the requirement of extraneous partitions to form the bulkheads or partitions and capable of being restored to their original condition without requiring the removal of parts from the cars and without loss of shipping space.

A further object is to provide house cars so arranged and constructed that portions of the car lining may be disposed to form bulkheads or partitions for dividing the cars into separate compartments wherein the portions of the lining carry locking means capable of locking these portions in partition-forming position and in lining-forming position.

A further object is to provide house cars equipped with spaced sliding doors so disposed that the front stop for one door serves as the back stop for an adjacent door.

A further object is to provide novel partitions for house cars embodying locking means.

Other objects of the invention will become clear as the description thereof proceeds.

In the drawings forming part of this specification:

Fig. 1 is a diagrammatic elevation of a portion of a house car embodying the instant invention.

Fig. 2 is a horizontal section taken on line 2—2 of Fig. 1, parts being shown diagrammatically.

Fig. 3 is a horizontal section taken on line 3—3 of Fig. 2.

Fig. 4 is a vertical section taken on line 4—4 of Fig. 3 looking in the direction of the arrows, parts being broken away to permit illustration on an enlarged scale.

5 Fig. 5 is an elevation of the structure of Fig. 4 looking toward the left in Fig. 4.

Fig. 6 is a vertical section taken on line 6—6 of Fig. 1.

Fig. 7 is a vertical section taken on line 7—7 10 of Fig. 1.

Fig. 8 is a horizontal section taken on line 8—8 of Fig. 1.

Fig. 9 is a horizontal section taken on line 9—9 of Fig. 1.

15 The drawings illustrate a preferred embodiment of the instant invention. In Fig. 1 of these drawings a portion of a railway house car, designated generally by the reference numeral 10, is shown diagrammatically. It is to be understood that the remaining portion of the car is complementary to the portion shown and that the side walls of the car are substantially similar in construction.

The side walls 11 and 12 embody side plates 13 25 and 14 upon which a roof, designated in its entirety by the reference numeral 15, is supported. The side plates are substantially Z-shaped in section and are formed with depending flanges 16 and 17, respectively. These flanges extend from 30 webs 18 and 19 from the inner edges of which flanges 20 and 21 extend upwardly. The flanges 20 and 21 are bent, as clearly shown in Fig. 3 of the drawings, to form flanges 22 and 23 which conform to the slope of the roof 15.

35 The side wall 11 embodies door posts for the main intermediate door, one of these posts being shown at 24. The side wall 11 also embodies a plurality of intermediate posts 25 and end posts, one of which is shown at 26. The door posts,

40 intermediate posts and end posts are secured at their upper ends in any desired manner to the side plate 13 and at their lower ends in any desired manner to a side sill 27. Metallic sheathing 28 is secured to the outer faces of the posts as well as to the side plate and to the side sill in any desired manner, as is understood in the art. A lining 29, preferably formed of wood, is secured to the inner faces of the intermediate and end posts and to nailing blocks, one of which 45 is shown at 30, fastened to the door posts 24.

The side wall 12 embodies a plurality of door posts for the main door, one of these posts being shown at 31. The side wall 12 also embodies a plurality of intermediate posts 32 and end posts 50 33. The door posts, intermediate posts and end

posts are fastened at their upper ends in any desired manner to the side plate 14 and at their lower ends in any desired manner to the side sill 34. Metallic sheathing 35 is secured in any desired manner to the outer faces of the posts and at its upper and lower margins to the side plate 14 and to the side sill 34. An inner lining 36, preferably formed of wood, is secured to the inner faces of the intermediate and end posts and to nailing blocks carried by the door posts, one of these nailing blocks being shown at 37.

The ends of the cars are closed by means of end walls, extending between and secured to the side walls 11 and 12. One of the car ends is shown in its entirety at 38.

It is frequently desirable to provide a number of separate compartments in a railway house car. This desirability arises when less-than-carload shipments are being transported so that each of these shipments may be loaded and unloaded without disturbing any of the other shipments in the car. By providing separate compartments in the car, shipment of less-than-carload lots of commodities can be made.

Heretofore a plurality of compartments have been obtained in various ways, all of which have involved additional labor and additional parts. Compartments have been provided by means of bulkheads or partitions which are removed from the car when it is desired to ship carload lots of commodities. Additional members are, therefore, required for the bulkheads. Labor is involved in positioning and fastening these members in the car and when they are removed, they are required to be stored and then returned to point of origin as deadweight for further use.

Compartments have also been provided by means of bulkheads which constitute a part of the permanent equipment of the car. In this case these bulkheads, when not in use, are stored either against the ends of the car or adjacent to the roof of the car. They constitute additional deadweight which must be carried when they are not being utilized and, moreover, reduce by their bulk the cubical capacity of the car and, hence, its revenue producing ability.

The instant invention provides a construction of railway house cars whereby separate compartments are obtained when desired by a structure which is a permanent part of the car construction but which does not require any extraneous members and does not reduce the cubical capacity of the car when not used to provide the compartments. In addition, this invention secures independent accessibility of each of the compartments.

To this end a portion 39 of the lining 29 and a portion 40 of the lining 36 are hinged to the side walls 11 and 12, respectively, in a manner hereinafter described. As more clearly illustrated in Fig. 2 of the drawings, the lining portions 39 and 40 are preferably thicker than the remainder of the linings 29 and 36 so as to provide greater strength against thrust. However, the inner faces of the lining portions 39 and 40 lie substantially in the same plane as the inner faces of the remainder of the linings 29 and 36 so as not to reduce the cubical capacity of a car. It is to be understood that the lining portions 39 and 40 may be of the same thickness as the remainder of the linings 29 and 36, if desired.

Each of the lining portions 39 and 40 is preferably formed of a plurality of vertically arranged tongue and groove boards 41 and 42, respectively. The upper and lower margins of the lining por-

tions 39 are reinforced by means of angles 43 and 44 and the lining portion 40 is reinforced by means of angles 45 and 46. The hinged margin of the lining portion 39 is preferably reinforced by means of a substantially T-shaped member 47 and the lining portion 40 is preferably reinforced by means of a substantially T-shaped member 48. The free ends of the lining portions 39 and 40 are rabbeted, as indicated at 49 and 50, so that the inner faces of these lining portions may lie in the same plane as the remainder of the lining portions 29 and 36.

As more clearly shown in Fig. 2 of the drawings, the lining portions 39 and 40 are illustrated in full lines in their lining-forming position and in dot and dash lines in their partition-forming position. To assume the latter position, the lining portions 39 and 40 are swung toward the longitudinal center line of the car so as to lie transversely thereof and cooperate to form a partition which divides the car into several compartments. The particular structure shown for the purpose of illustrating the invention provides two sets of lining portions 39 and 40 capable of dividing the car into three separate compartments. It will be understood, of course, that the invention is not limited to its illustrated form but that any desirable number of lining portions may be utilized to provide the desired number of compartments.

Each compartment, formed as described hereinabove, is made accessible independently of each other compartment from both sides of the car. In the illustrated embodiment of the invention this accessibility is obtained by means of openings in each side of the car opposite the hinged lining portions 39 and 40. Thus, door openings, such as 51, are formed in the side wall 11. Each of these door openings, which may be smaller than the main door opening 52, as better illustrated in Fig. 1 of the drawings, is defined in part by means of door posts 53 and 54 which carry nailing blocks 55 and 56 to which the fixed portions of the lining 29 are secured. The lining portion 39 spans the door opening 51 and is hinged to the door post 53 as hereinafter explained in connection with the lining portion 40. Each of the door openings 51 is adapted to be closed by means of a sliding door 57 accessible for operation from the outside of the car. Closing movement of the door is limited by means of a front stop 58. Any desired sliding door construction may be utilized to close each of the door openings 51.

To provide accessibility from the side wall 12 to the compartment formed by the lining portions 39 and 40, a door opening 59 is provided. This door opening, which is preferably similar in size to the door openings 51, is defined in part by means of door posts 60 and 61. These posts carry nailing strips 62 and 63 to which the fixed portions of the lining 36 are secured. The lining-forming portion 40 spans the door opening 59 which is adapted to be closed by means of a sliding door 64 operable from the outside of the side wall 12. The door 64, which may be of any desired construction, is limited in its closing movement by means of a front stop 65.

As noted hereinabove, one of the door posts of each of the door openings 51 and 59 serves as a means for hinging the lining portions 39 and 40. With particular reference to Fig. 8 of the drawings, it will be seen that this is accomplished by means of a hinge 66, one leaf 67 of which is secured as by means of rivets 68 to the T-shaped

reinforcing member 48. The other leaf 69 of the hinge is shaped to conform to the door post 60 and is secured thereby as by means of rivets 70 and 71. To permit attachment of the hinge leaf 69 to the door post 60 a portion of the nailing block is removed as indicated at 72. This mode of attachment is utilized in hinging each of the lining portions 39 to a door post.

Means is provided for securing the lining portions 39 and 40 in lining-forming position and in partition-forming position and in accordance with the instant invention the same means is utilized for both purposes. As best illustrated in Figs. 4, 5, 6, and 8, each of the securing means, a plurality of which are preferably used to lock each of the lining portions 39 and 40, comprises a main body portion 73 in the form of a round bar disposed in a vertical opening 74 positioned intermediate the inner and outer faces of the lining portions. As more clearly shown in Fig. 8 of the drawings, the vertical opening 74 is formed by cutting away portions of adjacent boards used to form the lining portions 39 and 40 so that the main body portion 73 of the locking means is slidable within the opening. The lower end of the body portion 73 extends through an opening 75 formed in the bottom reinforcing angle so as to engage a keeper secured to the floor of the car as hereinafter explained.

To the upper end of the body portion 73 a locking element 76 is secured as by means of welding. The locking element 76 is substantially T-shaped in section and embodies a rectangular stem 77 slidable through a rectangular opening 78 formed in the upper reinforcing angle. The locking element 76 also embodies oppositely extending flanges 79 and 80 which are provided with depending flanges 81 and 82, respectively.

In order to actuate the fastening means a handle 83 is secured, as by means of a rivet 84, to the body portion 73. Sufficient space for grasping the handle 83 is provided by removing a portion of the lining portion as indicated at P in Fig. 4 of the drawings. Access through the lining portion is prevented by means of a metallic plate 85 to which an angle member 86 is secured as by means of rivets 87 and serves to limit upward movement of the locking mechanism through engagement with the handle 83.

Keepers are provided in the car for engagement with the locking means in order to lock the lining portions 39 and 40 in desired position. In the illustrated embodiment of the invention angle members, such as 88, extending between and secured to the side plates 13 and 14 in any desired manner are formed with a plurality of openings 89 which constitute keepers as hereinafter explained. Additional keepers are carried by the side plates 13 and 14. One of these keepers 90 is illustrated in Fig. 6 of the drawings and as there shown is in the form of an angle member secured as by means of rivets 91 to the depending flange of a side plate. The inwardly extending leg 92 of the keepers 90 is formed with an opening 93.

Keepers extending transversely of the car are secured to the floor. As more clearly shown in Figs. 4 and 5 of the drawings, each of these keepers 94 comprises a substantially channel-shaped elongated body 95 formed with attaching flanges 96 and 97 and attaching flanges 98 and 99. The keepers 94 are set into the floor of the car as more clearly shown in Figs. 4 and 5 of the drawings, and are secured by means of rivets 100 and 101 which extend through the flanges 96 and 97

and 98 and 99 and a plate 102 disposed against the underside of the floor 103 of the car. It will be observed from Fig. 5 of the drawings that the body 95 of the keepers 94 slopes upwardly as indicated at 104 so as to permit the keepers to be cleaned readily.

Keepers 105, similar to the keepers 94, are arranged in longitudinally spaced relationship adjacent to each of the door openings 51 and 59. As more clearly shown in Fig. 6 of the drawings, the keepers 105 are disposed below the threshold plate 106 which is coped as indicated at 107 to permit engagement between the lower end of the body portion 73 of the locking means and the keepers 105.

When the lining portions 39 and 40 are in lining-forming position, as shown in full lines in Fig. 2 of the drawings, they are secured in this position so as to constitute a part of the car linings by the locking means hereinabove described. When in lining-forming position the lining portions are locked to the side plates of the car by the projection of the depending flanges 81 of the locking means through the openings 93 in the horizontal flanges of the keepers 90. The lining portions are also locked to the floor of the car by the engagement between the projecting ends of the body portions of the locking means and the longitudinally spaced keepers 105.

The lining portions 39 and 40 are locked in partition-forming position to the angle member 88, extending transversely of the car and secured to the side plates 13 and 14, and to the floor of the car. Securement to the angle member 88 is obtained by the extension of the depending flanges 82 of the substantially T-shaped locking elements 76 through the openings 89 formed in the angle member 88. The lining portions 39 and 40 are fastened to the floor of the car by the engagement of the projection of the body portions 73 with the keepers 94.

To release the locking means so that the lining portions 39 and 40 may be swung to lining-forming or partition-forming position, the handle 83 is raised, thereby effecting disengagement between the depending flanges 81 or 82 from the keepers 93 or 89 and disengagement of the projections of the body portions from the keepers 94 or 105. Raising of the locking means is limited by the angle member 86. It is to be observed that rotation of each locking means is prevented by the shape of the stem 77 and the openings 78 in the upper reinforcing angles. It will be apparent, moreover, that by reason of the disposition of the body portion 73 of the locking means intermediate the inner and outer faces of the lining portions 39 and 40, no loss of loading space occurs when the lining portions are in lining-forming position.

As illustrated, and as preferred, release of the locking means so that the lining portions may be swung from lining-forming to partition-forming position is effected from the inside of the car which is accessible through the main door openings in the side walls. These openings are closed by means of sliding doors 108 and 109. The construction of these doors may be as desired. Closing movement of these doors is limited by means of front stop members such as 110 similar in construction to the front stop members for the doors 57 and 64. By means of the instant invention the arrangement of the sliding doors, all of which are operable from the outside of the car is such as to reduce the number of parts normally required for sliding doors. This is accomplished

by the relationship between the doors whereby the front stop, which serves to limit closing movement of one of the doors, is capable of functioning as a back stop for limiting opening movement of an adjacent door. In this manner the customary back stops employed with sliding car doors and the labor in the application of the back stops are eliminated. This purpose is effected in the illustrated embodiment of the invention by having front door stop 110 serve as a means for limiting the opening movement of the door 57 and the front door stop 65 of the door 64 serve as limiting means for the main door 109. It will be understood that a similar relationship is provided between the main doors 108 and 109 and the doors similar to doors 57 and 64 carried by the side walls on the opposite side of the main doors.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A railway house car comprising side walls each embodying an inner lining, sections of said linings being hinged at a vertical edge to said side walls and swingable toward each other to form a vertical partition, locking means carried by said sections cooperable with means in said car for locking said sections in partition-forming position, said locking means being cooperable with other means in said car to lock said sections in lining-forming position.

2. A railway house car comprising side walls each embodying an inner lining, sections of said linings being hinged at a vertical edge to said walls and swingable toward each other to form a vertical partition, said sections being thicker than the remainder of said linings, the inner face of each of said linings lying in substantially the same plane, locking means carried by said sections cooperable with means in said car for locking said sections in partition-forming position, said locking means being cooperable with other means in said car to lock said sections in lining-forming position.

3. A railway house car comprising side walls embodying inner linings, sections of said linings being hinged and swingable toward each other transversely of said side walls to form a partition, said hinged lining sections being thicker than the remainder of said linings, the inner face of each of said linings lying in substantially the same plane, and means carried by said hinged lining sections for locking the same in partition-forming position, said locking means being disposed between the faces of said hinged lining sections and projecting beyond the top and bottom edges thereof, said locking means being also adapted to lock said hinged lining sections in lining-forming position.

4. A railway house car comprising side walls each embodying an inner lining, sections of said linings being hinged at a vertical edge to said side walls and swingable toward each other to form a plurality of spaced vertical partitions dividing said car into a plurality of compartments, means for locking said partitions, and a door for each compartment operable from the outside of said car and permitting independent access to each of said compartments.

5. A railway house car comprising side walls each embodying an inner lining, sections of said

linings being hinged at a vertical edge to said side walls and swingable toward each other to form a plurality of spaced vertical partitions dividing said car into a plurality of compartments, means for locking said partitions, and a door for each compartment operable from the outside of said car and permitting independent access to each of said compartments, said doors in closed position lying opposite said hinged lining sections.

6. A railway house car comprising side walls, side plates, a roof, and a floor, said walls embodying inner linings, sections of said linings being hinged and swingable toward each other transversely of said walls to form a partition, locking means carried by said sections, keepers carried by said car adjacent to said roof, keepers secured to said floor, said locking means engaging said first mentioned keepers and certain of said floor keepers to lock said sections in partition-forming position, and keepers secured to said side plates, said locking means engaging said latter keepers and others of said floor keepers to lock said sections in lining-forming position.

7. A railway house car comprising side walls each embodying an inner lining, sections of said linings being hinged at a vertical edge to said side walls and swingable toward each other to form a vertical partition, means for locking said lining sections in partition-forming position, and means for locking said lining sections in lining-forming position.

8. A railway house car comprising side walls, side plates, a roof, and a floor, said walls embodying inner linings, sections of said linings being hinged and swingable toward each other transversely of said walls to form a partition, locking means carried by said sections, a bar secured to and extending across said car adjacent to said roof, spaced openings in said bar, keepers secured to said floor and keepers secured to said side plates, said locking means engaging said openings in said bar and certain of said floor keepers to lock said sections in partition-forming position, said locking means engaging others of said floor keepers and said side plate keepers to lock said sections in lining-forming position.

9. A railway house car comprising side walls, a floor, a roof, and a side plate, a partition in said car extending between said side walls to form a plurality of compartments, locking means carried by said partition, keepers carried by said car adjacent to said roof, keepers in said floor spaced transversely of said car, said locking means engaging said keepers to lock said partition, keepers secured to said side plate and longitudinally spaced keepers in said floor adjacent to a wall of said car, said locking means engaging said side plate keepers and said latter floor keepers to lock said partition in non-partition-forming position.

10. A railway house car comprising side walls, side plates, a roof and a floor, said walls embodying inner linings, sections of said linings being hinged and swingable toward each other transversely of said walls to form a partition, locking means carried by said sections, keepers carried by said car adjacent to said roof, transversely spaced keepers in said floor, said locking means engaging said keepers to lock said sections in partition-forming position, keepers secured to said side plates, and longitudinally spaced keepers in said floor adjacent to said walls, said locking means engaging said side plate keepers and said latter floor keepers to lock said sections in lining-forming position.

11. A railway house car comprising side walls each embodying an inner lining, sections of said linings being movable toward each other from lining-forming position to a vertical position between said side walls to form a partition extending between said side walls transversely of said car, means for locking said sections in partition-forming position, and means for locking said sections in lining-forming position.

12. A railway house car comprising side walls, side plates, a roof, and a floor, said walls embodying inner linings, sections of said linings being hinged and swingable toward each other transversely of said walls to form a partition, locking means carried by said sections, said locking means embodying a unitary slidable bar disposed between the faces of said sections, and a locking element secured to said bar and extending beyond the upper edge of said sections, said locking element having depending locking bolts, said bar projecting beyond the lower edge of said sections, keepers carried by said car adjacent to said roof, transversely spaced keepers in said floor, certain of said locking bolts engaging said keepers adjacent to said roof and said projection of said bar engaging said floor keepers to lock said sections in partition-forming position, keepers carried by said side plates and longitudinally spaced keepers in said floor adjacent to said walls, the other locking bolts engaging said side plate keepers and said bar projection engaging said latter floor keepers, to lock said sections in lining-forming position.

13. A railway house car comprising side walls, side plates, a roof, and a floor, said walls embodying inner linings, sections of said linings being hinged and swingable toward each other transversely of said walls to form a partition, locking means carried by said sections, said locking means embodying a unitary slidable bar disposed between the faces of said sections, and a locking element disposed adjacent to the upper edge of said sections and being operable by said bar, said

bar projecting below the lower edge of said sections, keepers carried by said car adjacent to said roof, transversely spaced keepers in said floor, said locking element engaging said keepers adjacent to said roof and said bar projection engaging said floor keepers to lock said sections in partition-forming position, keepers carried by said side plates and longitudinally spaced keepers in said floor adjacent to said walls, said locking element engaging said side plate keepers and said bar projection engaging said latter floor keepers to lock said sections in lining-forming position.

14. A bulkhead for railway house cars comprising a main body section adapted to extend transversely of said car to divide the car into separate compartments, a unitary bar slidably disposed between the faces of said section, the lower end of said bar projecting below the lower edge of said section when in locking position, a substantially T-shaped locking element secured to said bar, said locking element having flanges extending transversely of said section adjacent to the upper edge thereof, the flanges of said locking element being provided with depending locking bolts.

15. A bulkhead for railway house cars comprising a main body section adapted to extend transversely of said car to divide the car into separate compartments, a unitary bar slidably disposed between the faces of said section, the lower end of said bar projecting below the lower edge of said section when in locking position, a substantially T-shaped locking element secured to said bar, said locking element having flanges extending transversely of said section adjacent to the upper edge thereof, the flanges of said locking element being provided with depending locking bolts, a recess in said section, and an operating handle disposed in said recess and fastened to said bar, said handle lying between the faces of said section.

FRANK DITCHFIELD.
